UNITED STATES PATENT OFFICE.

ROBERT MIEHLE, OF CHICAGO, ILLINOIS, ASSIGNOR TO CONTINENTAL & COMMERCIAL TRUST & SAVINGS BANK, TRUSTEE, OF CHICAGO, ILLINOIS.

SHEET-DELIVERY MECHANISM.

1,111,668.

Specification of Letters Patent.

Patented Sept. 22, 1914.

Application filed July 22, 1912. Serial No. 710,933.

To all whom it may concern:

Be it known that I, ROBERT MIEHLE, citizen of the United States, residing at Chicago, in the county of Cook, and State of Illinois, have invented a certain new and useful Improvement in Sheet-Delivery Mechanism, of which the following is a full, clear, concise, and exact description, reference being had to the accompanying drawings, forming a part of this specification.

My invention relates to sheet-delivery mechanism and is of particular service when employed in connection with printing presses for delivering printed sheets therefrom.

My invention, in one of its aspects, relates to mechanism for feeding slip sheets between freshly printed sheets so as to prevent the printing from off setting. I employ a belt, or a plurality of belts, preferably pivotally anchored at one end and secured at the other end to a roller having a spring mechanism that exerts winding torque upon the roller. The roller is caused to travel in a uniform direction in a substantially fixed orbit and to this end it may be mounted upon similar stretches of adjacent endless belts whereby the roller is caused to move toward and from the turning anchorage for the belt, or belts, attached thereto. Spring mechanism is provided for exerting winding torque upon the roller but I do not limit myself to this characteristic, and while the belt, or belts, attached to the roller are preferably provided with turning anchorages, I do not wish to be limited to that characteristic.

My invention in another of its aspects resides in the employment of a sheet supporting belt, or belts, a feed board along which sheets are conveyed toward the sheet supporting belt in a direction opposite to that in which the sheet supporting stretch of such belt is moving and a device interposed between the sheet supporting belt and the feed board for reversing the direction in which the sheets that are fed upon the sheet supporting stretch of the belt in the same direction, in which such belt stretch is moving. This feature of my invention enables me to economize space since the feed board may partially or completely overlie the sheet supporting belt instead of being located in alignment with such belt. I have employed the present feature of my invention for the

purpose of feeding slip sheets between printed sheets and by means of the invention no additional space need intervene between the sheet supporting belt and the printing press for the purpose of feeding slip sheets between the printed sheets.

My invention, in another of its aspects, besides broadly in means for initially feeding or delivering sheets in opposing directions, there being means employed for unifying these directions before the sheets are deposited and I consider this feature of my invention to be broadly new whether or not sheet conveying belts are employed.

I will explain my invention more fully by reference to the accompanying drawing showing the preferred embodiment thereof and to which embodiment the invention is not to be limited and in which drawing—

Figure 1 is a side view illustrating a portion of the printing press and the sheet delivery mechanism of my invention; Fig. 2 is a view, on a larger scale, of the sheet delivery mechanism shown in Fig. 1, the rollers to which the sheet conveying belts are attached being shown in positions differing from their positions in Fig. 1 (it being possible by means of my invention to employ two sheet conveying belt supporting rollers); Fig. 3 is a plan view of most of the parts as they appear in Fig. 1; and Fig. 4 is a detail of one of the rollers upon which torque is exerted by spring mechanism.

Like parts are indicated by similar characters of reference throughout the different figures.

The impression cylinder 1 is illustrated as being of the two revolution type coöperating with a type or form bed but obviously the nature of the press is immaterial to the invention. The sheets 2 after being printed upon by the press are conveyed by belts 3 in time to be engaged by grippers 4, which may be of any suitable or preferred construction which need not be specifically described. These grippers are mounted upon opposite sides of a continuously traveling endless belt element 5 having suitable ratio of speed with respect to the speed of travel of the sheets 2 in order that the grippers may be in position to receive said sheets. The design illustrated being such that each set of grippers serves to engage a sheet 2, though the machine need not be limited to this design. The lower stretches of the belts 5, through

the intermediation of the grippers 4, pull the sheets 2 in the direction in which they are to be conveyed. When one of the sets of grippers 4 first engages a sheet 2, an associate roller 6 is just in advance thereof. When the other set of grippers 4 first engages a sheet 2, another roller 7 peculiar to this second set of grippers is just in advance thereof. These rollers 6 and 7 are mounted upon opposite sides of an endless belt element 8. Sheet supporting belts 9 are anchored to the rollers 6 and 7 and inasmuch as the embodiment of the invention illustrated includes two sets of belts 9 and two rollers 6 and 7, the ends of the belts 9 companion to those anchored to the rollers 6 and 7 are turningly anchored, one set of belts 9 having one turning anchorage and the other set of belts 9 having another turning anchorage, these anchorages being independent.

In order to anchor the belts 9 I preferably employ anchoring rings or collars 10 that are free to move about a shaft 11 common thereto. The belts 5 are located above the belts 8 and suitable gearing is employed to cause the adjacent stretches of belts 5 and 8 to move in the same direction whereby the sets of grippers 4 keep company with their associate rollers 6 and 7 until the grippers leave the plane of the lower stretches of the belts 5 and the rollers leave the plane of the upper stretches of the belts 8. Thus as the grippers 4 continue to pull the sheets 2 the belts 9 are unwound from their rollers in opposition to the coiled springs 12, moving in the manner of an ordinary roller shade, though there is no holding pawl mechanism since the belts 9 are either being drawn from their rollers in opposition to the springs 12 or are being wound upon their rollers through the agency of such springs. When the grippers 4 are about to leave the plane of the lower stretches of the belts 5 they release their holds upon the sheets 2 so that said sheets are fully deposited upon the belts 9. The rollers then leave the plane of the upper stretches of the belts 8, and when entering upon and traveling in the lower plane of the stretches of such belts 8 the springs 12 operate to turn the rollers and wind the belts 9 thereupon so that the sheet supporting lengths of the belts are decreased until finally they are removed altogether from beneath the sheets 2 which are deposited in a pile as indicated at 13.

It is obvious that my invention in certain of its aspects is realized where there is but one roller 6 or 7 and but one set of belts 9 and one set of grippers 4 but I preferably so embody my invention that two rollers 6 and 7 may be employed as well as two sets of grippers 4 and in such case the two belt elements 9 are provided with turning anchorages 10 and 11 as indicated, the anchorages of the two belt elements 9 being collocated

and preferably, though not necessarily capable of independent movement. These anchorages are located within the orbit of travel of the belts 6 and 7 in order that the two sets of belts 9 may not interfere. Where but one set of belts 9 is employed it is obvious that the non traveling anchorage for such belts need not be pivotal and need not be located within the orbit of the travel of the roller 6 or 7 to which such belts are attached. While I prefer to employ the belts 8 for descending in substantially fixed orbit of travel over the rollers 6 and 7 and prefer to employ springs 12 for winding the belts 9 upon the rollers when said rollers are moving toward the non traveling anchorage of such belts, I do not wish to be limited to such an arrangement as modifications are obvious.

The shaft 11 carries sheet stop fingers 13¹ that are fixed thereupon so that the sheets 2 are arrested and are thereafter allowed to proceed in time to permit the grippers 4 properly to grasp the same, see Fig. 1.

Any suitable gripping mechanism may be employed for the grippers 4 and suitable mechanism for controlling the operation of these grippers may be used. As illustrated one gripper 14 of each pair is fixed with respect to one link of its carrying chain 5, while the gripper 15 companion to the gripper 14 is pivotally mounted upon another link of said chain. The spring 16, when free to operate, brings the gripper 15 into gripping engagement with a sheet 2 interposed between the grippers. A segmental gear 17 is fixed with respect to the gripper 15. A segmental rack 18 is journaled upon a shaft 19. A cam roller 20 has a mounting upon the segmental gear 18 by which the axis of said roller and said gear 18 are relatively fixed. A cam 21 is provided for each cam roller 20 and serves to move the associate segmental gear 18 to move the jaw 15 from its companion 14 whereby the sheet 2 may be fed into the space between the jaws 14 and 15. After the cam 21 has been passed the spring 16 will bring the jaw 15 toward the jaw 14 to grip the interposed sheet 2. Each cam roller 20 is also provided with a cam 22 whereby the jaw 15 is again moved away from the jaw 14 in order that the sheet 2 which now has been conveyed sufficiently far may drop out of the space between the jaws 14 and 15 preparatory to its complete deposit upon the belts 9 that support it.

The supporting belts 9 may also be employed to convey sheets 23. These sheets may be in the nature of slip sheets to prevent off setting of the printed sheets, but I do not wish to be limited to this characteristic. The sheets 23 are provided upon a feed board 24 and are initially fed therefrom in a direction opposite to that in which the sheets 2 enter upon the belts 9. A guide structure 25 serves to reverse the direction

in which the switches 23 move so that the forward ends of these sheets will enter into engagement with the grippers 4 and will be fed toward the same as are the sheets 2. 5 Where the sheets 23 are used as slip sheets they are superposed upon the sheets 2, the upper surfaces of these sheets 2 being the printed surfaces, the forward ends of each sheet 2 and a superposed sheet 3 being 10 simultaneously engaged by a set of grippers 4. One set of grippers 4 thus grips one pair of sheets 2, 23, and the other set of grippers 24 grips the next pair of sheets 2, 23, each 15 set of grippers thus alternating.

I believe it to be new with me initially to feed the sheets 2, 23, in opposing directions and thereafter to unify these directions whether such sheets be caused to travel one superposed upon the other and whether or not 20 such sheets are provided with belt conveyers for effecting farther travel thereof after they have been moved in similar directions. When the grippers 4 grip the sheets 2 and 23 in pairs these sheets are included in the same 25 pile 13 and this operation is of advantage whether or not the sheets 23 are slip sheets. It is obvious however that the gearing may be so designed as to cause one set of grippers 4 to grasp sheets 2 only and the remaining set of grippers to grasp the sheets 23 only whereby the sheets 2 and 23 are alternated in the pile 13, this operation being of advantage whether or not the sheets 23 are slip sheets.

Any suitable mechanism may be provided 35 for feeding the sheets 23 through the segmental guiding element 25. I have employed finger stops 26 operated at suitable intervals by printing press operated lever mechanism 27 to be brought into position at regular intervals for the purpose of designing the time at which the sheets 23 may enter the segmental guide structure 25 and properly to position said sheets prior to 40 their travel through such guide structure. Printing press operated lever mechanism 28 serves to raise the rollers 29 when the sheets 23 are to be adjusted against the fingers 26. After an interval has elapsed which is sufficient 45 to permit of the proper adjustment of each sheet 23 against the fingers 26, the rollers 29 are lowered into engagement with the driven rollers 30, the rollers 29, (which are idlers) and the rollers 30 co-operating to 50 feed the sheets 23 through the segmental guide structure 25.

Reference may be had to my co-pending application Serial No. 676,096, filed February 7, 1912, and Serial No. 768,604, filed 55 May 19, 1912.

I believe I have described in sufficient detail the mechanism by which one embodiment of my invention may be secured. It is obvious that many changes may be made 60 in the structure without departing from the

spirit of the invention and I do not therefore wish to be limited to the precise details of construction shown, but

Having thus described my invention I claim as new and desire to secure by Letter Patent the following:

1. Sheet delivery mechanism including a sheet supporting belt element anchored at one end; a roller to which the other end of said belt element is attached; means for causing said roller to travel substantially in an orbit; and means for causing the roller to wind the belt element thereupon when the roller approaches the anchorage for the belt element.

2. Sheet delivery mechanism including a sheet supporting belt element anchored at one end; a roller to which the other end of said belt element is attached; an endless belt element upon which said roller is mounted whereby said roller is caused to travel substantially in an orbit; and means for causing the roller to wind the sheet supporting belt element thereupon when the roller approaches the anchorage for the sheet supporting belt element.

3. Sheet delivery mechanism including a sheet supporting belt element anchored at one end; a roller to which the other end of said belt element is attached; means for causing said roller to travel substantially in an orbit; and spring mechanism for turning the roller when it approaches the anchorage for the sheet supporting belt element then to wind said sheet supporting belt element upon the roller.

4. Sheet delivery mechanism including a sheet supporting belt element anchored at one end; a roller to which the other end of said belt element is attached; an endless belt element upon which said roller is mounted whereby said roller is caused to travel substantially in an orbit; and spring mechanism for turning the roller when it approaches the anchorage for the sheet supporting belt element then to wind said sheet supporting belt element upon the roller.

5. Sheet delivery mechanism including two sheet supporting belt elements; a turning anchorage for one end of each of said belt elements, these anchorages being substantially collocated; a roller to which the other end of each of said belt elements is attached; means for causing said rollers to travel substantially in opposite sides of an orbit; and means for causing the rollers to wind the belt elements thereupon when the rollers approach the anchorages for the belt elements, said anchorages being within said orbit.

6. Sheet delivery mechanism including two sheet supporting belt elements; a turning anchorage for one end of each of said sheet supporting belt elements, these anchorages being substantially collocated; a roller

- 4
- to which the other end of each of said sheet supporting belt elements is attached; a belt element for causing the rollers to travel substantially in opposite sides of an orbit; and means for causing the rollers to wind the belt elements thereupon when the rollers approach the anchorages for the belt elements, said anchorages being within said orbit.
7. Sheet delivery mechanism including
- 10 two sheet supporting belt elements; a turning anchorage for one end of each of said belt elements, these anchorages being substantially collocated; a roller to which the other end of each of said belt elements is attached; means for causing said rollers to travel substantially in opposite sides of an orbit; and spring mechanism for turning the rollers when they approach the anchorages for the sheet supporting belt elements
- 15 then to wind said sheet supporting belt elements upon the rollers.
8. Sheet delivery mechanism including
- 20 two sheet supporting belt elements; a turning anchorage for one end of each of said belt elements, these anchorages being substantially collocated; a roller to which the other end of each of said sheet supporting belt elements is attached; a belt element for causing the rollers to travel substantially in opposite sides of an orbit; and spring mechanism for turning the rollers when they approach the anchorages for the sheet supporting belt elements then to wind the said sheet supporting belt elements upon the
- 25 rollers.
9. Sheet delivery mechanism including a sheet supporting belt element anchored at one end; a roller to which the other end of said belt element is attached; means for causing
- 30 said roller to travel substantially in an orbit; means for causing the roller to wind the belt element thereupon when the roller approaches the anchorage for the belt element; gripping mechanism for gripping
- 35 sheets; and means for causing said gripping mechanism to travel with said roller when sheets are being deposited upon said belt element.
10. Sheet delivery mechanism including
- 40 two sheet supporting belt elements; a turning anchorage for one end of each of said belt elements, these anchorages being substantially collocated; a roller to which the other end of each of said belt elements is attached; means for causing said rollers to travel substantially in opposite sides of an orbit; means for causing the rollers to wind the belt elements thereupon when the rollers approach the anchorages for the belt elements, said anchorages being within said orbit; gripping mechanism for gripping
- 45 sheets; and means for causing said gripping mechanisms to travel with said rollers when sheets are being deposited upon said belt elements.
11. Sheet delivery mechanism including
- 50 two sheet supporting belt elements; a turning anchorage for one end of each of said belt elements, these anchorages being substantially collocated; a roller to which the other end of each of said belt elements is attached; means for causing said rollers to travel substantially in opposite sides of an orbit; means for causing the rollers to wind the belt elements thereupon when the rollers approach the anchorages for the belt elements, said anchorages being within said orbit; gripping mechanisms for gripping
- 55 sheets; and means for causing said gripping mechanisms to travel with said rollers when sheets are being deposited upon said belt elements.
12. Sheet delivery mechanism including
- 60 two sheet supporting belt element anchored at one end; a roller to which the other end of said belt element is attached; means for causing said roller to travel substantially in an orbit; means for causing the roller to wind the belt element thereupon when the roller approaches the anchorage for the belt element; gripping mechanism for gripping
- 65 sheets; and means for causing said gripping mechanism to travel with said roller when sheets are being deposited upon said belt element.
13. Sheet delivery mechanism including
- 70 two sheet supporting belt elements; and means for alternately placing each belt element above the other whereby each belt element, when uppermost, may receive a sheet and thereafter place the sheet it supports in a lower position when such belt element may have the sheet it supports discharged therefrom.
14. Sheet delivery mechanism including
- 75 two sheet supporting belt elements; means for alternately placing each belt element above the other whereby each belt element, when uppermost, may receive a sheet and thereafter place the sheet it supports in a lower position when such belt element may have the sheet it supports discharged therefrom; and means for increasing the length of each belt element when uppermost then to receive the sheet.
15. Sheet delivery mechanism including
- 80 two sheet supporting belt elements; means for alternately placing each belt element above the other whereby each belt element, when uppermost, may receive a sheet and thereafter place the sheet it supports in a lower position when such belt element may have the sheet it supports discharged therefrom; and means for decreasing the length of each belt element when lowermost then to discharge the sheet.

16. Sheet delivery mechanism including two sheet supporting belt elements; means for alternately placing each belt element above the other whereby each belt element, when uppermost, may receive a sheet and thereafter place the sheet it supports in a lower position when such belt element may have the sheet it supports discharged therefrom; means for increasing the length of each belt element when uppermost then to receive the sheet; and means for decreasing the length of each belt element when lowermost then to discharge the sheet.
17. In a sheet delivery mechanism for printing presses and the like, the combination of an extensible and contractible sheet-carrying element; means to cause one end of said element to traverse an orbit; and means for substantially fixedly locating the other end of the element within the orbit whereby the movable end of the carrier travels around the substantially fixed end.
18. In a sheet delivery mechanism; the combination of a plurality of belt elements each anchored at one end; and means for alternately placing each belt element above the other to receive a sheet and for alternately placing each belt element below the other to lower the sheet it carries preparatory to its discharge.
19. In a sheet delivery mechanism, the combination of a plurality of belt elements each anchored at one end; rollers to which the unanchored ends of the belt elements are secured; and means for unwinding each belt element from its roller when such belt element is uppermost then to receive the sheet and for winding each belt element upon its roller when such belt element is lowermost then to discharge the sheet.
20. In a sheet delivery mechanism, the combination of a plurality of belt elements each anchored at one end; means for alternately placing each belt element above the other to receive a sheet and for alternately placing each belt element below the other to lower the sheet it carries preparatory to its discharge; and means for extending each belt element when uppermost then to receive the sheet and for contracting each belt element when lowermost to effect the discharge of the sheet.

In witness whereof I hereunto subscribe my name this twentieth day of July A. D., 1912.

ROBERT MIEHLE.
